UNITED STATES PATENT OFFICE.

EDWARD ERICKSON, OF BOSTON, MASSACHUSETTS, ASSIGNOR TO THE BOYLSTON MANUFACTURING COMPANY, OF BOSTON, MASSACHUSETTS, A CORPORATION OF NEW JERSEY.

HEEL-COMPRESSING MACHINE.

1,104,177.

Specification of Letters Patent. Patented July 21, 1914.

Application filed July 23, 1907. Serial No. 385,146.

To all whom it may concern:

Be it known that I, EDWARD ERICKSON, of Boston, in the county of Suffolk and State of Massachusetts, have invented certain new and useful Improvements in Heel-Compressing Machines, of which the following is a specification.

This invention relates to heel-compressing machines, and its objects are manifold.

10 The principal object of the invention is to compress all parts of a heel simultaneously and this is accomplished by providing complementary tread and heel seat dies, complementary side or edge dies, and a breast die, all of which are so constructed and arranged as to be actuated by a movement of a reciprocating head. Of these elements especial importance is given to the side and breast dies which utilize the power of the 15 machine most advantageously in compressing the heel from front to rear.

Another novel feature is the utilization of a pair of compressing members as a heel carrier which not only places a heel in compressing position but which subsequently takes the place of an ejector, by removing the heel to a discharge opening through which it may gravitate to a suitable receptacle. Other novel features in the construction and operation of the invention are 20 hereinafter described and claimed, and illustrated on the accompanying drawings forming a part of this specification of which,

Figure 1 is a front elevation of a compressing machine constructed in accordance with the invention. Fig. 2 is a right side elevation thereof. Fig. 3 is a plan view in section of the power-transmitting mechanism. Figs. 4, 5 and 6 are details of the 25 clutch-controlling mechanism. Fig. 7 is a vertical section on a larger scale of the compressing mechanism in normal or receiving position. Fig. 8 is a similar view of the same mechanism in compressing position. Figs. 9 and 10 are plan views, partly in section, of the same mechanism as it appears 30 respectively in Figs. 7 and 8. Fig. 11 is a front elevation partly in section of the mechanism as it appears in Figs. 8 and 10. 35 Before proceeding to the description of the machine it should be understood that the names and terms employed therein are not intended to limit the invention, but are solely for the purpose of designating the 40 several elements and their functions.

The same reference characters indicate the same parts wherever they occur.

Referring to the drawings it will be seen that the machine comprises primarily a stationary support 10 and a crosshead 20 movable toward and from the support. The said support and crosshead are provided, as usual, with a pair of coöperative compressing members, hereinafter described, between which a heel is to be compressed. 45 The support or bed, as it will be hereinafter termed, is supported by and between the up-standing sides 12, 12, which are formed on the bases 14, 14, of the frame. The crosshead 20, as illustrated, is above the bed 10, 50 though the order might be reversed, and its ends, which have guiding flanges 15, 15, extend through slots in the sides 12, 12 in which the ends have sliding bearing. Cylindrical projections 16, 16 formed on the 55 ends of the head 20 are connected respectively by links 17, 17 to a crank shaft 18 suitably journaled in bearings in the base portions 14, 14 of the frame. The head 20 is moved toward and from the bed 10 by rotating the shaft 18, and in order to properly rotate the shaft the machine is provided with a convenient form of power-transmitting mechanism hereinafter described.

As previously stated the bed 10 and head 20 are provided with coöperative compressing members. These members may be individually termed a tread die 19 and heel seat die 21, inasmuch as the former engages and flattens the tread of a heel, and the latter engages and forms that surface of the heel which is to lie against the heel seat of a shoe. The tread die 19 is in reality a metallic plate having a plane or flat work-engaging surface. Although it is 60 not absolutely necessary, it is preferable to have the die 19 stationary and the die 21 movable, and they are therefore mounted respectively on the bed and head as clearly shown in Figs. 7, 8 and 11. The member 19 is immovably installed in a depression in the bed so that its work-engaging surface lies flush with that of the bed. The member 21, however, is adjustably mounted by reason of being affixed to a die seat 22 65 having flanges 23 by which it is clamped to the head. Prior to clamping the die seat 22 in place, it may be provided with a heel seat die of any desired size or shape having dowel holes to receive the dowel 70

110

pins 24, and a screw thread hole by which it may be drawn up to the seat with a screw 25 set into the seat. The whole may then be slipped into a depression in the 5 head, and clamped in the correct position by the screws 20' and clamping strips 23' which overlap the flanges 23. In Figs. 1, 7, 8 and 10 it will be seen that there is a nose 26 which is a compressing member 10 in itself for it is adapted to engage the breast of a heel 100. The nose 26, herein-after termed a breast die, is of greater depth than a heel, and so the tread die 19 is provided with an aperture 27 to receive 15 the breast die so that the heel seat die may approach as closely as necessary to the tread die. The heel seat die is of convex form so as to shape a heel in conformity with the heel seat of a shoe, and it will 20 be seen in Figs. 7 and 8 that the median line of the work-engaging face thereof is inclined relatively to the head. The sliding bearing which the head has in the sides 25 of the frame, guides the head so that it moves perpendicularly toward and from the bed 10, and so the median line of the heel seat die and also the surface of the tread die 19, is inclined relatively to the direction in which the die moves. The 30 work-engaging surface of the breast die and the back face 46 thereof are also inclined to their direction of movement, all of which is hereinafter explained.

The combined heel-carrying and compressing mechanism, hereinbefore mentioned, 35 comprises primarily a pair of compressible dies 30, 30 adapted to engage the side and rear edges of a heel. These dies are movable in unison to and from the point of compression between the tread die 19 and heel seat die 21, and are also movable 40 toward and from each other so as to be adapted to compress the sides and rear of the heel. While their principal function 45 is that of compressing, they are instrumental, by reason of their unitary movement toward and from the point of compression, in acting as a carrier for carrying a heel to and from the said point. In 50 order to utilize the dies 30, 30 as a heel carrier they are preferably mounted on a carriage 31 which is mounted so as to move back and forth in guides 32 on a receiving table 33. A convenient method of mounting 55 the dies 30, 30 so that they shall be compressible is to pivot them on the carriage. In the form herein illustrated, they are provided with ears 34 which fit snugly in a recess in the carriage and which are 60 pivoted on a stud 35 common to both. See Figs. 7 and 8. Each member 30 constitutes a half-die, and both together form an orifice which in plan view conforms to the plan of the shape to which the heel is to 65 be compressed. The method by which the

members 30 are mounted makes it a simple matter to substitute others designed to give to a heel a different shape or size. A spring 36 occupying pockets 37, 37 formed in the inner faces of the members 30 near the 70 pivot 35, serves to normally separate the members on a line corresponding to the median line of a heel (see Fig. 9). By reason of so mounting the die members they are adapted to receive a heel blank from 75 above, and by reason of separating them and enlarging the passage between them a heel is free to gravitate therethrough unless supported by other means. For the purpose of supporting a heel in the dies, the carriage is provided with a plate 38, and means adapted to cause the plate to alternately cover and uncover the passage through the dies. A convenient method of 80 accomplishing this end is to utilize the movement of the carriage toward and from the point of compression. The plate 38 lies between the carriage and the table 33 and is adapted to have sliding contact with each. The plate is frictionally connected to the carriage by a stud 39 extending through a slot 40 formed in the plate parallel to the direction of travel of the carriage. The stud has a head 41 overlapping the sides of the slot 40, and drawn toward 85 the plate by a spring 42 compressed between the carriage and a nut and washer 43 on the other end of the stud. By this means the plate is frictionally clamped with yielding tension against the carriage, so that it is adapted to either move with 90 it or permit movement of the carriage relatively thereto within the limits of the slot. A friction washer may or may not 95 be inserted between the head 41 and the 100 plate 38.

The operation of the carrying and compressing mechanism is as follows. When the machine is in a state of rest, the said mechanism is as illustrated by Figs. 1, 2, 7 and 9. Referring now to Figs. 7 and 9, it will be seen that the head 20 bearing the heel seat die 21 and breast die 26, is relatively distant from the tread die 19, and that the compressible members 30, 30 of the heel carrier are in receiving position, also relatively distant from the tread die and point of compression. The dies 30, 30 are here separated by the spring 36 so that their rear shoulders abut against the carriage as shown in Fig. 9. A heel 100, placed tread first into the passage between the dies 30, 30 in this position, is supported therein by the plate 38 which now underlies the passage. The power-transmitting mechanism, herein-after described, is then brought into operation so as to advance the heel carrier toward the point of compression, and to actuate the several compressing members. As 115 the carriage 31 and die members 30, 30 ad- 120

vance, the plate 38, by reason of its frictional connection with the carriage also advances, still supporting the heel in the dies. On their way to the point of compression, 5 the dies 30, 30 and the forward end of the plate 38 pass over a discharge opening 44 in the table 33, through which the heel may be discharged as hereinafter explained. The plate 38 passing between the passage in the 10 dies and the opening 44 finally abuts against the bed 10 with which its work-engaging face is flush. Up to this point the tread *a* of the heel has been lying flat upon the plate 38 parallel with the direction of movement 15 of the dies 30, 30. Continued movement of the carriage and dies 30, 30 causes the latter to push the heel from the now stationary plate 38 to the inclined work-engaging face of the tread die 19, the stud 39 20 meanwhile advancing in the slot 40 of the plate. Having arrived at the point of compression the heel is tilted by the tread die so that the median line of the former is inclined to the movable work-engaging dies 25 and to their directions of movement. By reference to Figs. 8 and 10 it will be seen that the plate 38 is now retracted relatively to the opening in the dies 30, 30.

After the last named dies arrive at the 30 point of compression the slowly approaching heel seat die 21 and breast die 26 enter between the former dies, and engage respectively the top *b* and breast *c* of the heel. By reason of the inclination of the work-engaging face of the breast die, it crowds the heel toward the rear of the dies 30, 30, thereby compressing the breast *c* and rear *d* of the heel. The rear face 46 of the breast die is also inclined to its direction of movement but oppositely to the work-engaging face thereof. This face 46 is adapted to engage the inner faces of projecting portions 45, 45 formed on the dies 30, 30 and so to slightly wedge the side dies forward and 45 restrain the dies against tendency to retrograde movement, due to the pressure exerted on the heel by the breast die.

Simultaneously with the coöperation of the compression members 19, 21 and 26, the 50 dies 30, 30 are closed by suitable means so as to shape the side edges and rear portion of the heel. The means for accomplishing this may be of any preferred form, that illustrated having a pair of sliding pressure blocks 51, 51 mounted on the bed 10 and connected to the head 20 so as to be actuated thereby. The blocks 51, when the head is relatively distant from the bed 10, are separated as in Figs. 1 and 9 so that the dies 55 30, 30 may enter between them in approaching the point of compression. The blocks are preferably held against the bed by means such as the clips 52, 52 (Fig. 11) and are connected by pivoting 60 studs 53 to toggle links 54, 54 which in

turn are pivotally connected by studs 55, 55 to brackets 56, 56 formed on the head. By reason of this connection the head, as it approaches and leaves the bed, causes the blocks to alternately approach and recede 70 relatively to each other. As shown in Fig. 11 the heel seat die 21 is of just such size as to be admitted between the side dies 30, 30 when the latter are closed. In practice these three members are preferably combined in sets varying collectively in size and style, and are attached or detached as a whole. When the head 20 again recedes from the bed the carriage 31, together with the dies 30, 30 and plate 38, is retracted to 75 its former receiving position shown in Fig. 7. The plate 38 being retracted relatively to the passage between the dies 30, 30 again moves in unison therewith and the latter, being now released and separated, retracts 80 the compressed heel by means of the projecting portions 45, 45 of the dies. Continued movement of the carriage causes the plate to uncover the discharge opening 44 in the table 33, and causes the portions 45, 45 to move the heel to the said opening through which it is now free to gravitate. See Fig. 7. It is immaterial what becomes 85 of the heel but it may be presumed that it drops into a receptacle (not shown) below 90 the table. Before the carriage reaches its former receiving position the plate 38 engages another stop which arrests its movement and returns it to its former position relatively to the carriage and dies 30, 30. 95 This stop is shown as consisting of a pair of screws 48 set into the front edge of the table 33. See Fig. 10.

The description has so far covered a complete cycle of movements of the compressing 105 and carrying mechanisms, and while the mechanism for actuating the former forms no part of the invention, a brief description will make it somewhat clearer. The crank shaft 18 which effects the reciprocation of the head 20, also effects that of the carriage 31. For this purpose the shaft is provided with a path cam 60 whose path is occupied by a roll 61 mounted on a lever 62. One end of the lever is pivoted on a fixed shaft 63 115 mounted in the two base portions 14, 14, and the other end, which is connected to the carriage 31, has two forked extensions 64, 64 each formed with a radial slot 65. The carriage 31 has two bosses or arms 66, 66 which 120 extend through slots 67, 67 formed in the table, and which are connected by a rod or shaft 68 which passes through the slots in the extensions 64, 64. The lever 62 is oscillated by the cam 60 so as to reciprocate the 125 carriage in correct relation to the reciprocation of the head 20.

Rotation of the shaft is effected by a gear 70 affixed to the cam 60 and driven by a pinion 71 affixed upon a counter-shaft 72. 130

See Fig. 3. The shaft 72 is journaled in bearings 73 in the bases 14, 14 and is provided with a gear 74 which is driven by a pinion 75 affixed upon the primary power shaft 76 also journaled in bases 14, 14 by bearings 77, 77. The shaft 76 is provided with a continuously rotating loose pulley 78 having an annular internally tapered friction ring 79, and with a tight conical clutch member 80 adapted to have frictional driving engagement with said ring. The shaft 76 is also provided with a tight momentum wheel 81, and a controller 82 adapted to be manually actuated so as to force the loose pulley with its ring 79 into engagement with the tight member 80. Figs. 3, 4 and 6 illustrate a cylindrical cam member 83 which surrounds the shaft 76 and which is pinned or otherwise secured to a fixed support such as the bearing 77. The member 83 has inclined end faces 84 which are adapted to cooperate with correspondingly inclined faces 85 formed on one end of the controller 82. The controller also has a segment of gear teeth 86 which intermesh with a gear segment 87 affixed to one end of a rock shaft 88 journaled in bearings in the bases 14, 14. The arm of the segment is pivotally connected to one end of a link 89 whose other end is pivotally connected to a hand lever 90 pivotally mounted on one end of the shaft 63 and held thereon by a collar 91. The lever 90 is adapted to be manually actuated so as to cause the segment to oscillate the controller 82. When the controller is oscillated in one direction it is caused, by its engagement with the inclined faces 84 of the member 83, to move endwise on the shaft 76, and to engage the hub of the loose pulley 78 and force the ring 79 of the latter into driving relation with the cone member 80. In order to hold the parts in this relation, the hand lever is provided with a spring-pressed latch 92 which engages a toothed sector 93 secured to the frame 12. The rock shaft 88 may be provided with an arm 94 and a spring 95 connected thereto so as to exert on the rock shaft a tendency to return the controlling means to inoperative position. The rock shaft may also be provided with an arm 96 carrying a stud 97 and brake shoe 98 thereon adapted to engage the periphery of the momentum wheel 81 when the controlling means is in inoperative position.

In Figs. 1 and 2, the journals of the crank shaft 18, are shown as having removable lower caps 99 formed with screw-threaded shanks 101. The latter are provided with nuts 102 which have suitable seats in the base portions 14, 14 and which are adapted to lock the caps against their journal boxes in the frame.

Having thus explained the nature of my said invention and described a way of constructing and using the same, although with

out attempting to set forth all of the forms in which it may be made, or all of the modes of its use, I declare that what I claim is:—

1. A heel-compressing machine comprising a stationary die, and a plurality of movable dies, all of which have work-engaging faces inclined to the directions of movement of the movable dies. 70

2. A heel-compressing machine comprising movable side dies, a movable heel seat die, a movable breast die, and a tread support for the heel inclined to the direction of pressure of the dies. 75

3. A heel-compressing machine comprising a tread support for a heel, a heel seat die and breast die movable toward and from the heel support in a line inclined to the tread-engaging face thereof, and side dies adapted to compress between them an inclined heel. 80

4. A heel-compressing machine comprising a heel seat die movable in a given path, and having a work-engaging face whose median line is inclined to the path of movement, a coöperative die having a plane face 90 parallel to said median line and adapted to engage the tread of the heel, coöperative side dies adapted to surround the sides of a heel, and a breast die movable with the top die and adapted to enter between the side dies 95 and the heel breast, said breast die and side dies having coöperative faces inclined to the direction of movement of the former.

5. A heel-compressing machine comprising a relatively stationary element, a relatively movable element movable toward and from the stationary element, coöperative dies mounted respectively on the stationary and movable elements, and transversely movable coöperative dies mounted on the stationary 100 element, all of said dies having work-engaging faces adapted to inclose and compress a heel with its median line inclined to the directions of movement. 105

6. A heel-compressing machine comprising a stationary supporting die, a heel seat die movable toward and from the supporting die in a direction inclined to the supporting face thereof, and having a work-engaging face correspondingly inclined to the direction of movement, coöperative side dies adapted to compress a heel with its tread lying against the supporting die, a breast die fixed relatively to and movable with the heel seat die and having a breast-engaging face inclined to the direction of movement thereof, and means adapted to be engaged by the back of the breast die and to hold the die against the work. 115

7. In a heel-compressing machine, a vertically movable compressing die, a slidable carriage movable toward and away from the compressing position of said vertically movable die, laterally movable compressing dies mounted on said slidable heel carriage and 125 130

- independently movable thereon, and a heel support slidingly supported by said carriage.
8. A heel-compressing machine comprising a stationary support, a reciprocatory head movable toward and from the support, a pair of compressing members mounted respectively on the support and head, a carriage movable transversely toward and from the stationarily mounted compressing member, a pair of compressible dies mounted on the carriage so as to coöperate therewith in carrying a heel blank to a position between the said compressing members, an automatic slide movable in part with said second-mentioned members, and means on the stationary support connected to and operable by the head for compressing the compressible dies as the head approaches the stationary support.
9. A heel-compressing machine comprising a pair of compressing members of which one is movable toward and from the other, and a heel carrier movable toward and from the point of compression, said carrier comprising a carriage, a pair of compressible dies mounted thereon and constructed so as to form a passage through which a heel may gravitate, and arranged so as to enter between the compressing members, and a heel support frictionally connected to the carriage, and constructed and arranged so as to cover or uncover the said passage to either support or release a heel between the dies.
10. A heel compressing machine comprising a pair of side dies for compressing the sides and back of a heel, dies for engaging opposite faces and the breast of a heel contained in said side dies, means for closing said side dies, and means for closing the other dies to compress said opposite faces and breast while the side dies are compressing, said breast die being adapted to act on said side dies to compress the heel from front to rear.
11. A heel compressing machine comprising a tread die and a coöperative heel seat die, means for closing said dies, coöperative side dies arranged to compress laterally a heel engaged by said tread and heel-seat dies, a breast die fixed as to the heel seat die and arranged to engage the breast of a heel while the same is engaged by said tread die, heel-seat die, and side dies, and coöperative means on said breast die and side dies for effecting compressing movement of the side dies.
12. A heel compressing machine comprising coöperative top and bottom dies, a fixed support for one of said dies, a vertically movable head for the other, laterally movable side compressing dies, means for closing said side compressing dies, and a breast-engaging die adapted to move the heel laterally against the side dies, and to move the side dies in the opposite direction against the heel, said side dies having means for engaging the back of the breast die to effect the aforesaid movement against the heel.
13. A heel compressing machine comprising top and bottom dies, one movable toward and from the other, means for closing said dies, laterally movable side dies arranged to compress a heel laterally while the heel is engaged by said top and bottom dies, said side dies being also movable laterally from compressing position to a remote position, a slide for supporting a heel blank in said side dies at said remote position, said slide being movable with said side dies toward said bottom die, means for causing said slide to move with said side dies toward and from said bottom die, said means permitting relative movement of said side dies and slide, and stops for arresting movement of said slide.
14. A heel compressing machine comprising top and bottom dies, one movable toward and from the other, means for closing said dies, laterally movable side dies adapted to compress a heel blank laterally while the heel is engaged by said top and bottom dies, said side dies being also movable laterally from compressing position to a remote position, a slide for supporting a heel in said side dies, said slide and side dies being movable together and relatively movable, and means for causing concerted movement and relative movement of said slide and side dies for effecting the delivery of a heel blank to said bottom die, and the discharge of the blank from said bottom die and side dies.
15. A heel compressing machine comprising top and bottom dies, one movable toward and from the other, means for closing said dies, laterally movable side dies adapted to compress a heel blank laterally while the heel is engaged by said top and bottom dies, said side dies being also movable laterally from compressing position to a remote position, a slide movable toward and from said bottom die and arranged to engage the bottom of a heel in said side dies and support the heel therein, and means for causing said slide to occupy heel supporting position with relation to said side dies while said dies are moving toward said bottom die, and to occupy non-supporting position while said dies are moving away from said bottom die.
16. A heel compressing machine comprising top and bottom dies, one movable toward and from the other, means for closing said dies, a heel support movable toward and from said bottom die transversely of closing movement of said dies, a pair of hinged side dies arranged above said heel support in the transverse plane of a heel resting upon said support, said side dies being movable transversely to and from the line of said top and bottom dies, and means

- for moving said support and side dies to deliver a heel to said bottom die, to remove the heel from said bottom die, and to discharge the heel from said support and side dies.
17. A heel compressing machine comprising top and bottom dies, one movable toward and from the other, means for closing said dies, a slideable heel support movable transversely toward and from said bottom die, a pair of hinged side dies arranged to engage the sides of a heel resting on said support, said side dies being movable in parallelism with said slide, and movable transversely of said slide but in a parallel plane, means for moving said side dies from a remote position to compressing position between said top and bottom dies, means for closing said side dies in compressing position, means for causing said heel support to move with said side dies toward and from said bottom die, and means for rendering said support alternately operative and inoperative at the end of each parallel movement of said side dies.
18. A heel compressing machine comprising compressing dies in fixed alignment, one of said dies being movable toward and from the other, a slideable heel support movable toward and from the coöperative point of said dies, and coöperative compressing members movable with relation to said slideable support and otherwise movable toward and from each other.
19. A heel compressing machine comprising a table having a discharge opening, compressing members above the table, said members being arranged and actuated to receive a heel blank from above, to compress it laterally, to move it laterally in a line passing over said discharge opening, and to release it, a slide between said table and compressing members, and means for causing said slide to cover and uncover said discharge opening, and to cover and uncover the opening between said compressing members.
20. A heel compressing machine comprising a pair of compressing members of which one is movable toward and from the other, a pair of compressing members movable in unison to and from the first pair, and arranged and constructed to receive between them a heel from above, to move with the heel to juxtaposition relative to the first pair, to operate therewith in compressing the heel, to move with the heel away from the first pair, and to release the heel so that it may drop therethrough, and a slide movable with said second pair of members part way toward the first pair for supporting a heel blank in said second pair.
21. A heel compressing machine comprising coacting compressing members, means for opening and closing said members in a substantially vertical line, a laterally movable member for carrying a heel blank part way toward said compressing members, and means for transferring a heel blank from said carrying member to the lower member of said compressing members.
22. A heel compressing machine comprising a support for a heel blank, said support being movable in a substantially horizontal plane, means for sliding a heel blank laterally from said support and for compressing it laterally, and coacting compressing members for otherwise compressing the heel blank contained in said laterally compressing means.
23. A heel compressing machine comprising coactive compressing members, the machine being open near the point of compression to provide for the discharge of the work, a supporting member movable laterally toward and from said compressing members in a line extending over said point of discharge for carrying a heel blank toward said compressing members and over said point of discharge, coacting dies movable laterally for removing a heel blank from said supporting member, for compressing it in conjunction with said compressing members, and for moving the compressed heel away from said compressing members to said point of discharge, and means for moving said supporting member away from said point of discharge to effect a gravity discharge of the heel.
24. A heel compressing machine comprising a reciprocatory support movable in a substantially horizontal plane for carrying a heel blank, coacting compressing members arranged to open and close in a substantially vertical line beyond the range of said support, coacting side dies movable in a plane parallel to that of said support for transferring a heel blank from said support to said compressing members, for compressing the blank laterally in conjunction with said compressing members, for moving the compressed heel away from said compressing members toward the point where it was removed from said support, and for releasing said heel, and means for retracting said support from said point to permit the heel to drop through said dies.
25. A heel compressing machine comprising coöperative dies for engaging and compressing the tread and heel seat of a heel blank, said dies exerting their pressure in a substantially vertical line, the tread and heel seat faces of said dies being inclined to the direction of compressing movement, said heel seat die being provided with a wedge-shaped breast die; and compressing dies movable laterally to and from compressing position in conjunction with said vertically acting dies, the work engaging portions of said laterally movable dies being inclined to accord with said vertically acting dies, said

breast die being arranged to act within and in conjunction with said laterally movable dies.

26. A heel compressing machine comprising coöperative dies for engaging and compressing the tread and heel seat of a heel blank, a breast die, and coöperative side dies for compressing the blank laterally, said side dies being movable transversely of their path of lateral compressing movement for transferring the heel blank, said side dies and breast die having coactive surfaces whereby said breast die is adapted to move said side dies to compress the blank longitudinally.

27. A heel compressing machine comprising means movable toward and from each other for engaging the tread and heel seat of a heel blank to compress the blank from top to bottom, coöperative members for engaging the back of the blank, and a member for engaging the breast of the blank, said back-engaging members having portions movable toward and from each other for engaging the sides of the blank to compress the blank laterally, said back-engaging members being operable by said breast-engaging member for compressing the blank from breast to back.

28. A heel compressing machine comprising a tread die, a heel seat die, one of said dies being movable vertically toward and from the other, the machine being formed to permit the work to gravitate when discharged at one point, a slide movable laterally over said point toward and from the line of said tread and heel seat dies, means for arresting the approach of said slide at a remote point, coactive side dies for moving a heel blank from said slide to the line of said tread and heel seat dies, for compressing the blank laterally in conjunction with said head and heel seat dies, for removing the compressed heel, and for releasing it at said point of discharge, and a breast die fixed with relation to said vertically movable die, said breast die being arranged to coact with said side dies, and having its breast surface inclined to its line of movement.

29. A heel compressing machine comprising means movable toward and from each other for engaging the heel seat and tread of a heel blank to compress the blank from top to bottom, coöperative means for engaging the breast and back of the blank to compress from front to rear, and means operated by said breast-engaging means for moving said back-engaging means toward said breast-engaging means.

30. A heel compressing machine comprising a tread-engaging die, a heel-seat engaging die, means for moving one of said dies in a vertical line to effect coaction of said dies, a plate movable toward and from the

line of said dies, for carrying a heel blank, the range of movement of said plate being entirely outside the range of said dies, side dies above said plate, said side dies being movable with the plate toward the line of the other dies, movable from the plate to the other dies for transferring the heel blank, movable toward each other for compressing the blank laterally, movable away from each other and away from said other dies for discharging the heel, and means for retracting said plate to enable the heel to drop from the side dies.

31. A heel compressing machine comprising a pair of coöperative work-engaging and compressing members in fixed alinement of which one is movable toward and from the other, and coöperative compressing members movable in unison into and out of alinement with the first pair of members, the latter members being adapted to place a heel blank upon and remove it from one of the members first mentioned.

32. In a heel compressing machine, coöperative work-engaging members, and means for operating them in vertical alinement to compress a heel between them, a laterally movable carriage for conveying a heel blank to the lower of said compressing members, and two pivoted side dies on said carriage, and movable laterally from a position away from said members into a position registering with said members, said side dies engaging only the sides of the heel, and means for operating said side dies to compress the heel laterally.

33. A heel compressing machine comprising a table having a discharge opening, compressing members above the table, said members being arranged and constructed to receive a heel blank from above, to compress it, to move with it across the discharge opening, and to release the heel so that it may drop therethrough and through the opening, and an automatically operated slide to open and close said discharge opening and the opening between the said compressing members.

34. A heel compressing machine comprising a pair of work-engaging and compressing members of which one is movable toward and from the other, a pair of compressing members movable in unison to and from the first pair, and arranged and constructed to receive between them a heel from above, to move with the heel to juxtaposition relatively to the first pair, to coöperate therewith in compressing the heel, to move with the heel away from the first pair, and to release the heel so that it may drop therethrough, an automatic slide movable with said second-mentioned members toward said first pair, and means for arresting the approach of said slide at a remote point.

35. A heel compressing machine compris-

ing a pair of compressing members of which one is movable toward and from the other, a carriage movable toward and from the point of compression, a pair of compressible dies mounted on the carriage and constructed so as to form a passage through which a heel may gravitate, and arranged to move with a heel to the point of compression, a slide movable relative to said carriage for supporting a heel between the dies during their approach to the points of compression, and means for arresting the approach of said support at a remote point.

36. A heel compressing machine comprising a pair of compressing members of which one is movable toward and from the other, and a heel carrier movable toward and from the point of compression, said carrier comprising a pair of compressible dies constructed to form a passage through which a heel may gravitate, a support movable with respect to said carrier for supporting a heel between the dies during their approach to the point of compression, and means for rendering the support inoperative before the said carrier reaches a compressing position.

37. A heel compressing machine comprising a pair of compressing members, the machine being open at a point where a heel may gravitate, a heel carrier for moving a heel to and from said compressing members, and comprising a carriage, means on the carriage constructed so as to form a passage through which a heel may gravitate, and arranged so as to pass across said point to and from the compressing members, a heel support frictionally connected to the carriage so as to move therewith or relatively thereto between said means and said point, and stops for stopping the support independently of the carriage so as to cause the support to either cover or uncover the passage in said means.

45. 38. A heel compressing machine comprising a pair of compressing members, the machine being open at a point where a heel may gravitate, and a heel carrier movable over said point to and from said compressing members, said carrier comprising a carriage, a pair of compressible dies pivotally mounted thereon and constructed so as to form a passage adapted to register with said point and through which a heel may gravitate, and a relatively movable heel support constructed and arranged to underlie the passage in said dies when the latter are relatively distant from or approaching said compressing members, and to move and remain away from under the passage when the dies are at and moving from compressing position.

39. A heel compressing machine comprising means movable toward and from each other for engaging the heel seat and tread of a heel blank to compress the blank from top to bottom, means for engaging the back of the blank, a member for engaging the breast of the blank, and means adapted to be engaged and moved by said member for causing compressing movement of said back-engaging means toward said member. 65

40. A heel compressing machine comprising means for compressing a heel blank from heel seat to tread, a breast die movable toward the plane of the tread from the heel-seat side of the blank, coöoperative dies for engaging the sides and back of the heel blank, and means operable by said breast die for moving said back and side-engaging 75 dies to compress the heel blank longitudinally. 80

41. A heel compressing machine, comprising means for compressing a heel blank from heel seat to tread, a movable breast die 85 for moving the breast of the heel blank to compress the blank longitudinally, coöperative dies for engaging the sides and back of the heel blank, and means operable by said breast die for actuating said coöperative 90 dies to compress the heel blank longitudinally.

42. A heel compressing machine comprising coöoperative compressing members for acting upon the tread and heel seat of a heel blank, and coöoperative compressing members for acting upon the sides and back of the blank, one of the first-named members having a portion for acting upon the breast of the blank, the second-named members being operable by said portion for compressing the blank from breast to back. 95 100

43. A heel compressing machine comprising coöoperative compressing members adapted to form a closed mold for a heel blank, 105 said members including relatively movable members for engaging the breast and back respectively of the blank, one of said members being movable from top to bottom with reference to the heel blank, said breast-engaging and back-engaging members having coactive surfaces at an angle to their relative top to bottom movement whereby said back-engaging members are moved to compress the blank from breast to back. 110 115

In testimony whereof I have affixed my signature, in presence of two witnesses.

EDWARD ERICKSON.
